UNITED STATES PATENT OFFICE.

WILLIAM LLOYD WEBSTER, OF NEW YORK, N. Y.

DESIGN FOR A TOOTHBRUSH HANDLE.

60,184.

Specification for Design.

Patented Jan. 3, 1922.

Application filed January 31, 1921. Serial No. 441,490. Term of patent 14 years.

To all whom it may concern:

Be it known that I, WILLIAM LLOYD WEBSTER, a citizen of the United States, residing in the city, county, and State of New York, have invented a certain new, original, and ornamental Design for Toothbrush Handles, of which the following is a specification, reference being had to the accompanying drawing, forming a part thereof.

Fig. 1 is a plan view, and Fig. 2 is a side elevation of a tooth brush handle showing my new and original design.

I claim:

The ornamental design for a tooth brush handle as shown.

WILLIAM LLOYD WEBSTER.
